UNITED STATES PATENT OFFICE.

JULIAN KENNEDY, OF PITTSBURG, PENNSYLVANIA.

ROLLING-MILL.

SPECIFICATION forming part of Letters Patent No. 664,645, dated December 25, 1900.

Application filed June 29, 1898. Serial No. 684,717. (No model.)

To all whom it may concern:

Be it known that I, JULIAN KENNEDY, of Pittsburgh, in the county of Allegheny and State of Pennsylvania, have invented a new 5 and useful Improvement in Rolling-Mills, of which the following is a full, clear, and exact description, reference being had to the accompanying drawings, forming part of this specification, in which—

10 Figure 1 shows in front elevation, partly in vertical section, the vertical rolls of a universal mill, said rolls being constructed in accordance with my invention. Fig. 2 is a vertical section on the line II II of Fig. 1. Fig. 15 3 is a horizontal section on the line III III of Fig. 1. Fig. 4 is a detail view, and Fig. 5 is a front elevation, showing the vertical and horizontal rolls of the mill.

In the drawings, 2 2 represent the vertical 20 rolls of a universal mill. The manner in which these rolls are supported in their housings and the manner in which they are adjustable is novel and constitutes part of my invention. The housings 3 of the horizontal 25 rolls have projecting from them in the manner of brackets supporting-bars 4 5, on which the frames carrying the bearings of the vertical rolls can slide. Each frame consists of two heads 6 6', in which the bearings of the 30 rolls are set and which are connected together by a preferably integral web 7. The head 6 fits over and is supported by the bar 4, and the head 6' is fitted on the bar 5. The vertical roll has its bearings in the heads 6 6', 35 as illustrated in Fig. 2, and the head 6' is supported by a post or support 8, which extends from the plunger 9 of a small hydraulic cylinder 10, connected with a constant source of water-pressure. One end of the post bears 40 on the head 6' and the other end on the plunger, and their ends are preferably rounded or formed like balls, so as to be freely yielding laterally. As shown in Fig. 1, the two vertical rolls are journaled and supported in 45 like manner, the parts of one being distinguished in the drawings from the other by the prime-mark.

In order that the rolls may be adjustable—that is, movable toward and away from each

other—I employ screw-shafts 11 11', which extend from end to end of the housings through the heads 6 and 6', respectively, of the two rolls, each shaft being made with a right and left hand thread, so that when the shafts are turned by suitable gearing 12 the frames carrying the bearings of the rolls sliding on the brackets 4 5 will approach or recede, according as the screws are driven in one direction or the other. The lateral strain exerted on the rolls when at work is thus taken up, 55 not by housings, as heretofore, but by the adjusting-screws 11 11', and the structure is therefore self-contained. In this respect, as well as in the supporting of the bearings of the rolls at one side on supporting-bars on 60 which they can slide back and forth and in the adjustment of the rolls as above described, my invention is distinctly novel. Heretofore it has been the practice to set the bearings of the rolls between horizontal guide-bars. The rolls are supported in every position of their adjustment by the posts 8, and as these posts are upheld by the yielding plungers of hydraulic cylinders the lateral 65 swinging motion of the posts necessary to permit the adjustment is made possible.

The horizontal rolls 13 14 of the universal mill illustrated in Figs. 2 and 5 have intermediate portions *b b*, which are plain and adapted to the shaping of slabs or plates, and 70 end grooves *c c c*. The vertical rolls 2 2 have such range of lateral adjustment that they can be moved out beyond the end of the horizontal rolls into the positions illustrated by dotted lines. This is important because it 75 enables the universal mill to be used not only in the ordinary manner of universal mills for the purpose of rolling slabs, but when the vertical rolls are drawn out laterally to the end of their adjustment the grooves of the 80 horizontal rolls may be used like those of billet-rolls. I may thus take an ingot of metal and after reducing it at the middle pass *b b*, by the conjoint action of the horizontal and vertical rolls, to proper dimensions to fit the 85 grooves of the horizontal rolls I may introduce it into said grooves and there complete 90 the reduction, or I may use the grooved passes 95

independently of the universal mill. The driving mechanism of the vertical rolls is also novel and of especial utility. Each vertical roll carries at the upper end of its neck a 5 worm-wheel 15, and in gear with each worm-wheel are two worms 16 16', mounted with feather-and-spline connection upon driving-shafts 17 17'. The two worms of each roll 16 16 or 16' 16' are carried in a box 18, and each 10 box has sleeves 19, which fit around the shaft and afford suitable bearings therefor. It will thus be seen that the worm-wheels 15 and the worms and boxes are carried by the respective rolls back and forth in their adjustment, the 15 worms sliding on the shafts 17 17', but preserving always their connection with the wheels. The worms 16 16 are of opposite pitch from the worms 16' 16' and the shafts 17 17' are oppositely rotated, so that the rolls 20 are driven in opposite directions in every position of their adjustment. In order to permit the worms to adjust themselves somewhat to the worm-wheels in order to accommodate wear of the bearings or teeth, I support the box 18 upon the frame of the roll, 25 not fixedly, but by a sliding connection 20, so that it may have a slight lateral motion. In such lateral motion the box will carry with it the two worms and will cause them to adjust themselves automatically, so as to fit perfectly with the worm-wheel and share equally 30 in the work of driving it.

It will be noticed that the box 18 forms a connection between the worms on the opposite sides of the worm-wheel, and this is a 35 very important function, since if the bearings or teeth of either of the worms should become worn the connection between them will cause the worms to share the work of 40 driving the wheel notwithstanding the fact of the wear. This function can be performed not only by the box constructed as shown in the drawings, but by other kinds of connecting mechanism, such as will occur to those 45 skilled in the art, and I intend to claim this broadly in this regard.

I prefer to make the box 18 so as to inclose the worms and the worm-wheel in the manner of a casing, as shown in Fig. 2, and to 50 provide it with a lid or cap 21. I may charge the casing with oil or grease, so as to keep the worms continually in contact with a pool of the lubricant. I also preferably inclose the neck of the roll within a loose collar 22, 55 so as to permit access of the lubricant therethrough onto the neck of the roll, and for the purpose of catching and directing the lubricant I may provide its brass or bearing with a flaring top.

60 The box 18 and the gearing inclosed within the same may be quickly and easily removed from the upper neck of the vertical roll by withdrawing the liners 23, which fit the dovetailed portion of the box 18. These liners 23 65 are held in their proper position by means of

bolts which pass through the lip portion of the liners and secure them to the sliding box. When the liners are removed, a crane or other suitable mechanism may be applied to the box to lift the same and carry it to any desired point without disturbing any of the other portions of the roll-carrying mechanism.

As the rolls are driven by worm-gearing applied to both sides of the worm-wheels, I apply the power to both sides thereof, thus dividing the friction at the points of contact of the gears, but much more than proportionately relieving the wear, which in the case of heavy loads is apt to be very destructive and to be the source of great trouble and expense 80 when the power is applied at one side only of the worm-wheel.

I do not limit the claims of the specification to an improvement in rolling-mills unless so stated therein; but

What I claim is—

1. Vertical rolls, having a bearing at each end, a slide-bar for each of said bearings upon which the bearings may slide, said slide-bars being on but one side of the rolls and secured to a suitable support, and a laterally and vertically movable support for the lower bearing of each of said rolls.

2. In a rolling-mill, a roll having a gear-wheel on its neck driven by gears mounted 95 on shafts on each side thereof, and a box or frame containing the gearing and supported by the bearing of the roll, said box or frame and gearing being movable laterally thereon to permit automatic adjustment of the parts.

3. In a rolling-mill, a roll having a gear-wheel on its neck driven by gearing on both sides thereof, two driving-shafts, and a box supported by the bearing of the roll and containing the gearing, said box being closed and adapted to contain a lubricant.

4. In a rolling-mill, a roll having at its end a worm-wheel, power-shafts at each side thereof, and worms on the shafts having traveling connections with the shafts and in gear with the worm-wheel so as simultaneously to transmit power thereto from the power-shafts.

5. In a rolling-mill, a roll, having a gear-wheel on its neck driven by gearing on both sides thereof, two driving-shafts, a box or frame supported by the bearing of the roll and slidable thereon and containing the gearing, said box being closed and adapted to contain a lubricant.

6. In a rolling-mill, rolls having at one end worm-wheels, power-shafts extending along the sides thereof, worms mounted on said shafts having traveling connections with the shafts and in gear with the worm-wheels, bearings for the rolls carrying said worms, 125 and adjusting mechanism whereby the bearings and rolls may be moved.

7. In a universal mill, the combination with a pair of main housings of slide-bars carried by said housings and extending beyond them,

and a pair of vertical rolls carried on the slide-bars and adapted to be separated a distance equal to or greater than the distance between the main housings, and mechanism for adjusting the position of the rolls.

8. In a rolling-mill, a vertical roll having a laterally-movable lower bearing, a cylinder having a plunger, and a connection between

10
said plunger and bearing, said connection being adapted to be moved laterally.

In testimony whereof I have hereunto set my hand.

JULIAN KENNEDY.
